BURNER FOR ARMY TYPE STOVES

James L. Breese, Santa Fe, N. Mex., assignor to
 Oil Devices, Santa Fe, N. Mex., a limited partnership of Illinois

Application October 28, 1942, Serial No. 463,601

14 Claims. (Cl. 158—91)

My invention relates to an improvement in fluid fuel burners and has for one purpose the provision of a burner for burning a wide variety of hydrocarbons.

Another purpose is the provision of a burner adaptable for relatively light stove units, such as are employed, for example, in the United States Army.

Another purpose is the provision of improved valve means for liquid fuel burners.

Other purposes will appear from time to time in the course of the specification.

I illustrate my invention more or less diagrammatically in the accompanying drawings wherein:

Fig. 1 is a vertical section;

Fig. 2 is a section on an enlarged scale on the line 2—2 of Fig. 1;

Fig. 3 is a section on an enlarged scale on the line 3—3 of Fig. 1;

Fig. 4 is a section on an enlarged scale on the line 4—4 of Fig. 1;

Fig. 5 is a section on the line 5—5 of Fig. 3; and

Fig. 6 is a section on the line 6—6 of Fig. 3.

Like parts are indicated by like symbols throughout the specification and drawings.

Referring to the drawings, I generally indicate any suitable stove or heating chamber having any suitable flue outlet passage 2 and removable access member or lid 3. It will be understood that the member 1 is generally circular in cross section.

4 is a base member having a bottom portion 5. Resting in the base member is an intermediate member or baffle generally indicated as 6 and including an offset portion 7 resting upon the upper edge of the member 4, and an upwardly extending flange 8 adapted to receive and prevent lateral movement of the lower edge of the member 1. The parts may be freely removable from each other and constitute a readily dismountable stove which may be employed, if desired, to burn solid fuel. For example, a grate may be inserted or supported in the member 6 in the central opening 9 thereof. 10 indicates an access opening available when the device is employed to burn solid fuels, for the removal of ashes and the like. It may be closed for example by the door 11, hinged as at 12. It will be understood that the aperture 10 is generally rectangular.

15 indicates the outer drum or cylinder of a pot type burner, which is shown as removably secured to the stove unit. The housing 15 has an end wall 16 having a preferably central air inlet aperture 17. 18 is a centrally apertured

flame ring closing the opposite end of the cylinder 15. It abuts against and is secured to the flange 20 of the pot 19, which in turn may be secured to the edge of the cylinder 15, as by any suitable screws 21. The space between the pot 19 and the cylinder 15 is supplied with air through the opening 17, and the air penetrates the interior of the pot 19 through a plurality of primary air inlet apertures 22, and in the form herein shown through a row of secondary air apertures 23.

It will be understood that what is provided is a so-called hydroxylating burner, the operation of which will later be discussed in greater detail. Surrounding the end of the pot 19 I illustrate an air deflecting guiding ring 24 having a plurality of offsets 25, which are effective to prevent spiraling of the air as it passes about the pot 19.

Extending inwardly from the flame ring 18 is 20 a rectangular neck 26, which is of a proper size substantially to fill and conform to the contours of the aperture 10 in the stove base member 4. Any suitable means may be employed for securing the parts together. I illustrate for example a bottom flange 27, which engages the exterior of the lower edge of the aperture 10, and a top flange 28, which engages the interior of the upper edge of the aperture 10. The side elements 29 of the neck 26 are notched at the bottom, as at 30, to hook over the lower edge of the aperture 10. A locking bracket 31, with any suitable securing screw or bolt 32, is employed to prevent any unintended displacement of the parts.

35 indicates a cup adapted to hold the supply of liquid fuel burned in the pot. It will be understood that once combustion is inaugurated the fuel in the cup 35 is evaporated by the heat of combustion and receives its primary air supply from the primary air inlets 22. The result is a formation of a primary mixture of air and vaporized hydrocarbon which, when it receives the secondary air supply through the apertures 23, produces a completely combustible mixture, which flows out through the aperture 18a of the flame ring 18 and through the neck 26, and burns with a flame which extends into the base 4 and even up into the chamber 1.

The fuel is supplied to the cup 35 through a discharge nozzle 36. The cup is supported by a 50 wire or support 37, having at its upper end a hook 38. This hook 38 may enter an aperture 40 of a valve control plunger 39. The fuel may reach the burner from any suitable source of supply through a pipe 41, which may communicate with a valve fitting generally indicated as 42. 43

indicates a valve seat fitting, screw threaded as at 44 into the bore of the member 42. It is provided with a conical or beveled seat portion proper 45, and a fuel passage 46. 47 indicates a valve plunger slidable in a sleeve 48, which extends outwardly from the fitting 43 and is provided with oil outlet apertures 49. 50 is a spring abutment at the end of the member 47, so formed as to permit free passage of the fuel. 51 is a spring compressed between the abutment 50 and the end of the fitting or member 43. It tends to move the valve plunger 47 to open position.

52 is a fuel gauging valve pin having an inclined surface 52a. The plunger also has an abutment surface 53, opposed to the valve seat 45 of the member 43. When the parts are in the position shown in Fig. 3, the valve is entirely closed, and no fuel passes. When the plunger 47 is moved to the right, referring to the position of the parts in which they are shown in Fig. 3, the valve seat 45 is cleared, and the pin 52, with its inclined surface 52a, serves to meter the fuel.

The member 42 is provided with a screw threaded extension 54, which is seated in a bore of a block generally indicated as 55, and is held in position by any suitable locking nut 56. The extension 54 is vertically slotted, as at 57. Pivoted in the slot 57, as by a pin 58, is the valve control lever 59. Abutting against one side of it is the adjustable screw 60, mounted in the inner end of the plunger 47. Extending from the opposite side of the lever is the pin 61, which extends through a slot 62 in the valve control plunger 39.

The valve control plunger is slidable in a bearing sleeve 63, mounted in a vertical bore in the block 55, which intersects the slot 57. It has an enlarged upper external screw threaded head 63a, and a lower screw threaded portion 64, about which is positioned any suitable locknut 65. The sleeve 63 is also slotted, as at 66, in line with the slot 62, and permits the pin 61 to pass therethrough and to have a substantial range of movement.

The spring 67 tends normally to raise the plunger 39. Its upward movement is limited by the adjustable pin 68, which is adjustable in the plug 69 of the control head 70, rotatable by any suitable handle 71. It will be understood that the rotation of the head raises or lowers the pin 68, thus normally urging the spring 67 to allow the plunger 39 to raise as high up as the setting of the pin 68 permits. The spring 51 has the same effect or tendency—that is to say, it thrusts the screw 60 against the lever 59 and that moves the pin 61 as far upwardly at its right end, referring to the parts in the position in which they are shown in Fig. 3, as the slot 62 and the pin 68 will permit.

It will be understood that when the valve is set the oil flowing along the bore 42a of the block 42, and thence down through the nozzle 36, drips into the cup 35. It will be understood that if for any reason the cup 35 receives too much oil and tends to overflow, the increased weight of the cup, plus the oil, is effective to move the plunger 39 downwardly until it has flexed the pin 61 and compressed the spring 51 and moved the valve to shut off position, illustrated in Fig. 3.

While this is important as a safety device, it also serves as a modulating control for the fuel, as for instance if the valve delivers a little more fuel than can be burned, the increase in the weight of the fuel in the cup 35 tends to move the valve towards closing position. And as the fuel

burns off and the weight is reduced, the valve again moves towards open position.

The above control means is supported on the pot 19 as follows: A Y-shaped fitting generally indicated as 75 is welded or otherwise secured to the upper side of the pot 19, as shown in Fig. 1. The Y extends through any suitable cutaway part of the outer shell 15, as at 76. The Y has one preferably vertical arm 77, into which fits a rounded bottom portion 78 of the block 55. The other arm 79 of the Y is provided with a removable plug 80 and serves as an access means, for example for lighting the burner. The Y may be surrounded by any suitable surrounding shell or cup 81.

It will be realized that, whereas I have described and illustrated a practical and operative device, nevertheless many changes may be made in the size, shape, number and disposition of parts without departing from the spirit of my invention. I therefore wish my drawings and description to be taken as in a broad sense illustrative or diagrammatic, rather than as a limitation to my precise showing.

The use and operation of my invention are as follows:

I provide a heater which is adaptable for use with a simple knockdown stove such as shown for example in Fig. 1, and which will burn a wide variety of fuels from crankcase oil to gasoline.

As above described, the burner is a pot type hydroxylating burner in which the final combustion mixture is formed by first mixing vaporized fuel with primary air and then completing the mixture with secondary air and burning the final mixture. The vaporization of the inflowing fuel takes place as a result of combustion already under way. Combustion, however, can readily be initiated by dropping a match or any other readily combustible material into the cup 35 after some fuel has been supplied thereto.

The cup 35 serves not merely as a means for holding the fuel for vaporization, but as a means for controlling the rate of flow of fuel to the burner, and as a safety device for preventing overflow. The cup 35 being suspended on the control plunger 39, the weight of the cup, plus the fuel in it, would tend to move the plunger 39 down and close the valve by flexing the lower end of the lever 59 to the left, referring to the position of the parts in Fig. 3. But one or both of the springs 51 and 67 may be made effective to resist this downward movement entirely when the cup 35 is empty, or has less than a predetermined minimum of fuel in it. As the level of fuel in the cup rises and as the weight therefore increases, the compression to which the springs are subjected progressively increases and may be set to insure a complete closure of the valve before the cup 35 overflows. Thus, if the fire goes out for any reason, the liquid fuel continues to flow until the increasing weight of the cup 35 serves to close the valve.

In addition to this safety feature, the cup is also effective during continuing combustion to move the valve toward closed position in response to an increase in the height of the fuel in the cup. Also, as long as combustion is continuous, the burning off of part of the fuel in the cup reduces the weight of the cup and again permits an increased flow of fuel.

The device may be adjusted at several points. The adjustment of the screw 60 and the screw 68 is preferably a matter of factory adjustment. But the user can set the pin 68 for the upward

movement of the plunger 38 and the opening of the valve, by rotating the head 78 by means of the handle 71. Thus, the burner can be set at low or at high, or at any desired intermediate setting.

I claim:

1. In combination, in a liquid fuel burner and control means therefor, a burner pot having a circumferential wall with a plurality of air inlet apertures therein, an open end and a closed end, a liquid fuel line extending from a fuel source to the pot and terminating in fuel delivering relationship to the pot, a valve in said liquid fuel line, control means for controlling the valve and for thereby varying or setting the rate of fuel flow past the valve to the pot, an open topped movable fuel vaporizing cup in the pot and surrounded by said circumferential wall and closed end, positioned to receive liquid fuel from said fuel line, and means movable with said cup for moving the valve toward closed position in response to an increase in the volume of liquid fuel in the cup.

2. In combination, in a liquid fuel burner and control means therefor, a burner pot, a fuel line for delivering fuel to said pot, a valve in said fuel line, manually controllable means for setting said valve, and additional means for affecting the position of said valve in response to variations in the weight of unvaporized liquid fuel, including a plunger, a valve actuating connection between said plunger and said valve, yielding means tending normally to urge said plunger in one direction, and a fuel vaporizing element connected to said plunger and adapted to receive the liquid fuel delivered to the pot and adapted, in response to variations in the weight of unvaporized fuel in the element, variably to oppose said yielding means.

3. In combination, in a liquid fuel burner and control means therefor, a burner pot, a fuel line for delivering fuel to said pot, a valve in said fuel line, manually controllable means for setting said valve, and additional means for affecting the position of said valve in response to variations in the weight of unvaporized liquid fuel, including a plunger, a valve actuating connection between said plunger and said valve, yielding means tending normally to urge said plunger in one direction, and a fuel vaporizing element connected to said plunger and adapted to receive the liquid fuel delivered to the pot and adapted, in response to variations in the weight of unvaporized fuel in the element, variably to oppose said yielding means, the manual control means for the valve including means for varying the limit of movement of the plunger in one direction in response to said yielding means.

4. In combination, in a liquid fuel burner and control means therefor, a burner pot, a fuel line for delivering fuel to said pot, a valve in said fuel line, manually controllable means for setting said valve, and additional means for affecting the position of said valve in response to variations in the weight of unvaporized liquid fuel, including a plunger, a valve actuating connection between said plunger and said valve, yielding means tending normally to urge said plunger in one direction, and a fuel vaporizing element connected to said plunger and adapted to receive the liquid fuel delivered to the pot and adapted, in response to variations in the weight of unvaporized fuel in the element, variably to oppose said yielding means, the valve actuating

connection between the plunger and the valve including a lever pivoted adjacent the valve and plunger and having one portion in contact with the valve and another portion in contact with the plunger.

5. In combination, in a liquid fuel burner and control means therefor, a burner pot, a fuel line for delivering fuel to said pot, a valve in said fuel line, manually controllable means for setting said valve, and additional means for affecting the position of said valve in response to variations in the weight of unvaporized liquid fuel, including a plunger, a valve actuating connection between said plunger and said valve, yielding means tending normally to urge said plunger in one direction, and a fuel vaporizing element connected to said plunger and adapted to receive the liquid fuel delivered to the pot and adapted, in response to variations in the weight of unvaporized fuel in the element, variably to oppose said yielding means, the valve actuating connection between the plunger and the valve including a lever pivoted adjacent the valve and plunger and having one portion in contact with the valve and another portion in contact with the plunger, and yielding means effective normally to urge the valve as far toward opening position as said lever will permit.

6. In combination, in a liquid fuel burner, a burner pot having a wall provided with a plurality of scattered air inlet apertures circumferentially spaced about the pot and located at various distances from the ends of the pot, a vertically movable liquid fuel vaporizing cup positioned within the pot and spaced from the wall thereof, some of said apertures being located above and some below said cup, a liquid fuel pipe extending from a fuel source toward the pot and terminating in fuel delivering relationship to the pot, a valve in said liquid fuel pipe, manually operative means for varying the setting of the valve and an actuating connection between the valve and the cup adapted to move the valve toward closed position in response to a predetermined weight of liquid fuel in the cup.

7. In combination, in a liquid fuel burner, a burner pot having a wall provided with a plurality of scattered air inlet apertures circumferentially spaced about the pot and located at various distances from the ends of the pot, a vertically movable liquid fuel vaporizing cup positioned within the pot and spaced from the wall thereof, some of said apertures being located above and some below said cup, a liquid fuel pipe extending from a fuel source toward the pot and terminating in fuel delivering relationship to the pot, a valve in said liquid fuel pipe, manually operative means for varying the setting of the valve and an actuating connection between the valve and the cup adapted to move the valve toward closed position in response to a predetermined weight of liquid fuel in the cup and yielding means tending normally to urge the valve toward open position.

8. In combination, in a liquid fuel heater, a chamber, a generally horizontally axised burner pot having an open end, in communication with the interior of said chamber, said pot having a wall provided with a plurality of scattered air inlet apertures circumferentially spaced about the pot and located at various distances from the open end of the pot, a liquid fuel vaporizing cup positioned within the pot and spaced from the wall thereof, some of the apertures of the pot being

located above and some below said cup, a liquid fuel pipe extending from a fuel source toward the pot and terminating in a fuel delivering nozzle aligned with said cup, a valve in said liquid fuel pipe and means for varying the position of said valve in response to variations in the volume of liquid fuel in said cup.

9. In combination, in a liquid fuel heater, an open ended pot having a wall provided with a plurality of scattered air inlet apertures circumferentially spaced about the pot and located at various distances from the ends of the pot, a liquid fuel vaporizing cup positioned within the pot and spaced from the wall thereof, some of the apertures of the pot being located above and some below the cup, a liquid fuel pipe extending from a fuel source toward the pot and terminating in a fuel delivering nozzle aligned with the cup, valve means in the liquid fuel pipe and means for varying the position of the valve means in response to variations of the volume of the liquid fuel in the cup.

10. In combination, in a liquid fuel heater, a chamber, a generally horizontally axised burner pot having an open end, in communication with the interior of said chamber, said pot having a wall provided with a plurality of scattered air inlet apertures circumferentially spaced about the pot and located at various distances from the open end of the pot, a liquid fuel vaporizing cup positioned within the pot and spaced from the wall thereof, some of the apertures of the pot being located above and some below said cup, a liquid fuel pipe extending from a fuel source toward the pot and terminating in a fuel delivering nozzle aligned with said cup, a valve in said liquid fuel pipe and means for varying the position of said valve in response to variations in the volume of liquid fuel in said cup and additional manually operable means for varying the position of said valve.

11. In combination, in a liquid fuel burner and control means therefor, an open ended burner pot having a wall with a plurality of air inlet apertures therein spaced circumferentially around the pot and located at various distances from the ends of the pot, a fuel vaporizing cup movably mounted in said pot and located intermediate the ends of the pot and above some of said air inlet apertures and below others, a fuel duct adapted to feed fuel to the interior of said cup, and means for varying the rate of flow of the fuel along said duct and to said cup in response to changes in the weight of the unvaporized fuel in the cup.

12. In combination, in a liquid fuel burner and

control means therefor, an open ended horizontal burner pot having a wall with a plurality of air inlet apertures therein spaced circumferentially around the pot and located at various distances from the ends of the pot, a fuel vaporizing cup movably mounted in said pot and located intermediate the ends of the pot and above some of said air inlet apertures and below others, a fuel duct adapted to feed fuel to the interior of said cup, and means for varying the rate of flow of fuel along said duct and to said cup in response to changes in the weight of the unvaporized fuel in the cup.

13. In combination, in a liquid fuel burner and control means therefor, an open ended burner pot having a wall with a plurality of air inlet apertures therein spaced circumferentially around the pot and located at various distances from the ends of the pot, a fuel vaporizing cup movably mounted in said pot and located intermediate the ends of the pot and above some of said air inlet apertures and below others, a fuel duct adapted to feed fuel to the interior of said cup, and means for varying the rate of flow of the fuel along said duct and to said cup in response to changes in the weight of the unvaporized fuel in the cup, said duct being out of contact with said cup and having a delivery end located above said cup.

14. In combination, in a liquid fuel burner and control means therefor, a burner pot having a circumferential wall with a plurality of air inlet apertures at various levels therein, an open end and a closed end, a liquid fuel line extending from a fuel source to the pot and terminating in fuel delivering relationship to the pot, a valve in said liquid fuel line, control means for controlling the valve and for thereby varying or setting the rate of fuel flow past the valve to the pot, an open topped movable fuel vaporizing cup in the pot and surrounded by said circumferential wall and closed end, positioned to receive liquid fuel from said fuel line, and means movable with said cup for moving the valve toward closed position in response to an increase in the volume of liquid fuel in the cup, said cup being located intermediate the highest and lowest air inlet apertures of said circumferential wall, the fuel within said cup being directly exposed to the radiant heat of combustion taking place within the pot, the exterior of said cup being also subjected directly to the radiant heat of combustion taking place within the pot and being of heat conducting material and adapted to conduct heat to the fuel within the cup.

JAMES L. BREESE.
